(57) **CLAIM**

I claim the ornamental design for exercise equipment, as shown and described.

DESCRIPTION

FIG. 1 is a perspective view of exercise equipment;

FIG. 2 is a frontal view thereof;

FIG. 3 is a right-side view thereof;

FIG. 4 is a left-side view thereof;

FIG. 5 is an under-side view thereof; and,

FIG. 6 is an overhead view thereof.

The broken lines shown represent unclaimed subject matter and form no part of the claimed design.

1 Claim, 6 Drawing Sheets
